UNITED STATES PATENT OFFICE.

WILLARD F. RICHARDS, OF BUFFALO, NEW YORK, ASSIGNOR TO GOULD COUPLER COMPANY, OF NEW YORK, N. Y., A CORPORATION OF WEST VIRGINIA.

DRAFT-GEAR FOR RAILWAY-CARS.

SPECIFICATION forming part of Letters Patent No. 760,757, dated May 24, 1904.

Application filed October 24, 1902. Serial No. 128,620. (No model.)

To all whom it may concern:

Be it known that I, WILLARD F. RICHARDS, a citizen of the United States, residing at Buffalo, in the county of Erie and State of New

5 York, have invented new and useful Improvements in Draft-Gears for Railway-Cars, of which the following is a specification.

This invention relates more particularly to a draft-gear for railway-cars in which the 10 coupler is carried at the outer end of a long draw-bar which is pivoted at its inner end or portion and is capable of an extended or relatively great lateral swing or movement. The gear is especially applicable to long cars—15 such, for instance, as street-cars—which are operated upon roads having relatively short or sharp curves.

One object of the invention is to provide a draft-gear of simple, strong, and durable construction in which the draw-bar is allowed 20 the maximum lateral swing and is adequately supported at all points of its movement.

Another object of the invention is the provision of a construction and arrangement of 25 the draft and buffing spring housing or case whereby it is free to swing with the draw-bar, so that the springs are always maintained in the direction of action of the draft and buffing strains.

30 In the accompanying drawings, consisting of two sheets, Figure 1 is a longitudinal vertical sectional elevation of the end portion of a car-floor frame and a draft-gear embodying the invention. Fig. 2 is a plan view thereof, 35 the platform being removed to expose the draft-gear. Fig. 3 is a horizontal section, partly in plan, showing the draw-bar swung to one side. Fig. 4 is a transverse vertical section through the spring housing or case. 40 Fig. 5 is a transverse vertical section through the supporting-carriage for the outer end of the draw-bar.

Like letters of reference refer to like parts in the several figures.

45 In the accompanying drawings the draft-gear is shown applied to a street-car-floor frame.

A A' represent, respectively, the central

or draft timbers and the side longitudinal platform-timbers, B the car end sill, and C 50 the platform end sill or end portion of the platform-floor.

D represents a support or bearing for the draft and buffing spring case or housing, which is shown at E. The bearing is in the form of 55 a casting and is provided at its rear upper portion with transverse flanges d d', which are secured by bolts or otherwise on the under side of the car end sill. The support is also provided with longitudinal side flanges 60 d'', which extend up beside and inside of the longitudinal draft-timbers, to which the flanges are secured by bolts or the like d''. The upper portion of the draft and buffing spring housing or case is cylindrical and extends up through and rotatably bears in a 65 circular opening in the horizontal plate of the support or bearing. The housing or case is preferably provided with an external annular flange or bead e', which extends laterally beneath and bears against a horizontal circular face on the under side of the support or bearing surrounding the bearing-opening for the housing or case. The housing or case is supported 70 in the hanger and permitted to turn freely 75 therein by wheels or rollers F, which are journaled on studs or axles f, secured in any suitable manner to the upper cylindrical portion of the housing or case, which is preferably provided with portions f' of increased 80 thickness to afford ample bearing-surface for the axles. The rollers or wheels travel upon a circular track or horizontal face surrounding the bearing-opening in the support for the housing or case. This construction enables a very free and unlimited horizontal rotation of the housing in the bearing or support, and the cooperating bearing faces or shoulders on the support and housing are of adequate dimension and strength to resist the 85 draft and buffing strains to which the housing is subjected.

G represents the draw-bar, and g the coupler, which is secured to or connected with the front or outer end of the draw-bar. The 95 draw-bar may be of any usual or suitable con-

struction. The draw-bar is provided at its inner or rear end with a longitudinal stem h , which projects through opposite openings in the lower rectangular portion of the spring housing or case. I, I' represent oppositely-arranged follower-thimbles, which loosely surround the draw-bar stem and are arranged to move longitudinally in the openings in the housing, through which the stem passes. The 10 thimble or follower I abuts at its outer end against a shoulder i on the draw-bar and is provided at its inner end with a flange adapted to bear against the inner face of the end wall of the housing or case. The other thimble or follower, I', is provided with a flange at its inner end, which abuts against the inner face of the rear wall of the lower portion of the housing or case and abuts at its other end against a shoulder or stop, formed on the 15 draw-bar stem in the present instance by a nut i' , screwed on the threaded inner end of the draw-bar stem and held from turning thereon by a key or pin i'' , arranged in a hole in the end of the stem. J, j represent, respectively, the usual outer and inner spiral draft and buffing springs. The springs surround the stem of the draw-bar and abut at their opposite ends against the opposing inner ends of the two thimbles or followers I, I'. 20 By this construction it is obvious that the draw-bar, with the spring housing or case, and the draft and buffing springs are free to swing to any extent in the bearing or support and the springs are always carried 25 around with the draw-bar, thereby always being retained in the direct line of action of the draft and buffing strains on the draw-bar. The coöperating bearing faces or shoulders on the support and housing are of ample dimensions and strength to resist the draft and 30 buffing strains and shocks to which the housing is subjected. The other end of the draw-bar is supported or held from sagging, and the housing is thereby relieved of any torsional or 35 twisting strains, due to the weight of the draw-bar and coupler, in the following manner: K represents a track which in the construction shown is composed of two separated horizontal rails which are supported beneath the 40 curved end sill or end portion of the car-platform. The rails are curved concentrically with the axis of the spring housing or case and are supported, for instance, by means of brackets k , which have horizontal lower ends secured to the under sides of the rails and horizontal upper ends which are secured to the longitudinal draft and buffing timbers by bolts k' or in any other suitable manner. L represents a hanging roller-carriage for the outer end of 45 the draw-bar. This carriage in the construction shown is provided with a yoke, through which the draw-bar passes, and with a bearing or projection l , which extends up between the separated curved rails of the track K. The 50 carriage is provided with wheels or rollers M,

which are journaled on suitable studs or axles which project from the bearing of the carriage and which are secured thereto in any well-known or preferred manner. This manner of supporting the outer or forward end of the draw-bar permits the latter to swing freely from one side to the other of the car. The movement is not limited or restricted by any hangers or supports for the track, and the latter is supported at its ends and intermediate 75 portions by the supporting-brackets, so that the track cannot sag and the carriage always has a firm horizontal support. Any suitable means may be employed for limiting the swing of the draw-bar. In the construction shown 80 the ends of the track-rails are turned up to provide stops for this purpose.

I claim as my invention—

1. The combination with the end sill, of a draw-bar pivoted at its inner end, a track supported above the outer end of the draw-bar curved concentrically with the draw-bar pivot, and extending from end to end of the end sill, and a traveling supporting-carriage for the outer end of the draw-bar hung on said track, 85 said carriage being of substantially the width of the outer end of the draw-bar whereby the latter can swing from end to end of said end sill, substantially as set forth.

2. The combination of a draw-bar, a draft-spring housing which supports the inner end of the draw-bar, one or more draft-springs in said housing, a bearing supported above said draw-bar on which said housing is rotatably mounted, a track supported above the outer portion of said draw-bar, and a movable supporting-carriage for the outer end of the draw-bar hanging from said track, substantially as set forth.

3. The combination of a draw-bar, a draft-spring housing which supports the inner end of the draw-bar and which is mounted to turn with the draw-bar, one or more draft-springs carried by said housing, a curved track supported above the outer portion of said draw-bar, and a movable carriage for the outer end of the draw-bar hanging from said track, substantially as set forth.

4. The combination of a draw-bar, a pivotal support for the inner end of the same, separated curved track-rails supported above the outer portion of the draw-bar, and a supporting-carriage for the outer end of the draw-bar provided with supporting-wheels which roll on said rails, substantially as set forth.

5. The combination of a draw-bar, a draft-spring housing which supports the inner end of said draw-bar, one or more draft-springs carried by said housing, a bearing for said spring-housing, supporting-wheels for said housing which travel on said bearing, and a support for the outer end of the draw-bar, substantially as set forth.

6. The combination of a draw-bar, a draft-spring housing which supports the inner end 130

of the draw-bar, a bearing for said housing provided with a circular bearing-opening and a surrounding track, said housing having a circular upper portion extending up through 5 said opening, supporting-wheels for said housing which travel on said track on said bearing, and means for supporting the outer end of the draw-bar, substantially as set forth.

7. The combination of a bearing provided 10 with a horizontal circular track, a draft-spring housing provided with supporting-wheels which travel on said circular track on the bearing, a draw-bar stem which extends through diametrically opposite openings in 15 said housing, followers loosely mounted between shoulders on said stem, and one or more draft and buffing springs arranged in said housing between said followers, substantially as set forth.
- 15 8. The combination with draft-timbers and

an end sill, of a bearing provided with transverse flanges secured to said end sill, and longitudinal vertical flanges secured to said draft-timbers, a draft-spring housing, supporting-wheels for said housing which travel on a circular track on said bearing, a draw-bar provided with a stem which projects through 25 openings in said draft-spring housing, followers loosely mounted in said housing between shoulders or stops on said draw-bar stem, and draft and buffing springs surrounding said stem between said followers, substantially as set forth.

Witness my hand this 22d day of October, 1902.

WILLARD F. RICHARDS.
